UNITED STATES PATENT OFFICE.

HARRY INGRAM, OF BROOKLYN, NEW YORK.

MACHINE FOR FORMING CLOSURE CAPS.

Application filed March 31, 1923. Serial No. 629,068.

The invention relates to means for forming in the sides of closure-caps inner annular recesses adapted to receive band-gaskets utilized for sealing against the flat sides of the tumblers, jars or the like to which the caps may be applied.

The caps are first stamped up from sheet metal, preferably thin flexible sheet aluminum, before they are submitted to the machine of my present invention, and in this stage said caps comprise a disk-top and a plain smooth annular skirt portion depending from the peripheral edge of said top. The closure caps thus partly formed are submitted to the machine of my invention, and therein and thereby the skirt portions of the caps are transformed, by a spinning and rolling operation, from their flat condition into a shape specially adapted to receive side seal gaskets and cooperate with the gaskets in creating an effectual side-seal against a tumbler or the like. The skirt portions of the partly constructed caps are, in accordance with my invention, formed inwardly on annular downwardly and inwardly inclined or converging lines through a horizontal intermediate section of the skirt, thus providing a shoulder extending toward the side of the receptacle for supporting a gasket and creating above this shoulder an annular recess offset from the side of the receptacle to receive the gasket supported on the shoulder and into which recess the gasket is deformed and strongly pressed by the application of the cap to the receptacle. The said annular recess is defined at its lower edge by the aforesaid shoulder, at its upper edge by the peripheral portion of the lower surface of the top of the cap and at its outer side by the upper portion of the skirt of the cap, said upper portion of the skirt and said peripheral portion of the top of the cap being left in their original shape and condition as given to them in the dies. In the formation of the aforesaid gasket supporting and recess-creating shoulder, I also form a narrow vertical flange out of the lower portion of the skirt of the partly constructed cap, this flange extending downwardly from the inner edge of said shoulder. The machine of my invention while transforming the plain flat skirt of the partly formed cap into the gasket-receiving shape described, leaves all parts of the cap smooth and free of perceptible wrinkles or the like.

The machine of my invention comprises a bed or plate against which the flat top of the cap is held, a forming-flange or rim at the edge of said plate having a groove and suitable surfaces against which the plain flat skirt of the cap is strongly pressed and rotated to impart to it the gasket-receiving shape hereinbefore described, a forming roll which receives and is less in diameter than the cap and is shouldered and surfaced to cooperate with said forming-flange or rim in shaping the said skirt, a spring acting to yieldingly cushion the pressure exerted against the plain skirt of the cap between said roll and said forming-flange or rim, and means for effecting a relative traveling movement between said forming-flange or rim and said roll, whereby the roll and cap are rotated against said flange. The machine preferably employs several of the forming-rolls in cooperation with one forming-flange or rim, so as to increase the capacity of the machine.

The invention will be fully understood from the detailed description hereinafter presented, reference being had to the accompanying drawings, in which:

Fig. 1 is a top view, partly broken away and taken in the direction of the arrow *a* of Fig. 4, of a machine constructed in accordance with and embodying the invention;

Fig. 2 is a vertical section through a portion of the same, taken on the dotted line 2-2 of Fig. 1;

Fig. 3 is a vertical section through a portion of the machine, taken on the dotted line 3-3 of Fig. 1;

Fig. 4 is a vertical section through the machine;

Fig. 5 is a side elevation, partly in section and partly broken away, of a modified construction of machine embodying some of the features of my invention;

Fig. 6 is a vertical section through the same, taken on the dotted line 6-6 of Fig. 5;

Fig. 7 is a vertical section, taken on the dotted line 7-7 of Fig. 8, of a further modified construction embodying some of the features of my invention, and

Fig. 8 is a top view, partly in section, of the same.

In the drawings, referring to Figs. 1 to 4 inclusive, 10 designates an angularly disposed bed-plate or table constituting a por-

- tion of a machine frame and having throughout a large portion of its periphery an upstanding flange 11 formed with an undercut groove 12 having a plain flat side surface 13, and an upwardly and outwardly inclined surface 14, said surface 14 commencing at the upper edge of the surface 13 and terminating at the lower edge of a flat surface 15 which extends to the upper surface 10 of the rim or flange 11, as shown in Fig. 4. The bottom of the groove 12 is flat and is formed by the outer edge portions of the flat upper surface of the plate or table 10. The inner surface of the flange 11 constitutes a grooved runway against which the plain side of a cap is rotated by means of rolls 16 and which in cooperation with the rolls transforms the plain partly constructed closure-cap shown in Fig. 2 to the recessed cap shown in Fig. 3, the recess being annular and smooth and adapted to receive a suitable gasket which, with the cap, constitutes a side-seal closure for tumblers, jars and the like. The table 10 has a flat top 25 against which the flat tops of the caps ride, and said table is formed with a downwardly extending sleeve 17 (Fig. 4) within which is mounted a shaft 18 upon whose lower end is a beveled gear-wheel 19 and upon whose upper end is keyed a frame 20 having, in the present instance, three arms 21 which are hollow in their outer end portions and receive slidable bars 22 carrying the rolls 16 at their outer ends and at their inner ends being pressed against by coiled springs 23 confined within the arms 21, as shown in Fig. 4. The arms 21 are slotted, as at 24, and pins 25 extend through these slots and through the bars 22, whereby the movement 40 of the bars 22 is limited and said bars are confined to the arms 21. The arms 21 are all alike and likewise the bars 22 are all alike and each bar 22 at its outer end has an aperture to receive the axle of one of the rolls 16. The rolls 16 are arranged to rotate on ball bearings, as shown in Fig. 3, and each roll has a flat lower surface, an annularly projecting shoulder 26 which conforms exactly to the shape of the groove 12 in the flange 11, said shoulder 26 having a flat surface 27 to match the surface 13 of said groove and an inclined surface 28 to match the inclined surface 14 of said groove. The rolls 16 also have, outwardly beyond 55 the inclined surface 28, a plain peripheral surface 29 matching and extending outwardly beyond the flat surface 15 of the flange or rim 11, as represented on an enlarged scale in Fig. 3.
- 60 The shaft 18 carrying the arms 21 may receive its motion from any suitable source and at present I illustrate a driving shaft 30 mounted over the base-plate 31 and carrying a gear-wheel 32 in mesh with the gear-wheel 19 on the shaft 18.

In Fig. 2 I illustrate the closure cap 33 in its initial partly formed condition as fed to the machine of my invention and by which machine said cap, by a spinning or rolling operation, has its skirt portion given 70 the outline represented in Fig. 3, this outline conforming to the outline of the groove 12 in the flange or rim 11 and that of the portions 27, 28 and 29 of the rolls 16, whereby an annular recess 34 is provided in said 75 cap at the upper peripheral edges thereof, said recess being formed by the top of the cap and the sections 35, 36 of the skirt portion of the cap, a flange 37 being formed at the lower peripheral edges of said recess 34 80 and extending downwardly from the lower peripheral edge of the inclined section 36 of the skirt portion of the cap. The caps are, while inverted, fed to the machine in the condition in which they are shown in 85 Fig. 2, having plain straight annular skirts, and leave the machine in the form in which they are shown in Fig. 3 having the recess 34 and skirt sections 35, 36, 37. The purpose of forming the recesses 34 in the skirt 90 portions of the caps is to provide for the reception and retention of gaskets within the outer peripheral portions of the caps to seal against the sides of the tumblers, jars or other receptacles to which the caps may be 95 applied.

The caps, in the condition shown in Fig. 2, are fed to the machine on an inclined shelf 38 at one edge of the plate or table 10, as shown in Figs. 1 and 2, wherein the caps are numbered 33. The table 10 has an inclined pocket 39 into which the caps pass from the feed table 38, and as the rolls 16 reach the caps 33 in the pocket 39, the forward edge of the roll engages the then higher portion of the cap 33 (Fig. 2) and draws the cap upwardly upon the main flat flooring of the table 10 and carries the cap against the forming edge flange or rim 11, whose starting end 40 (Fig. 1) is adjacent to the pocket 39. The caps, one after another, are engaged by the rolls 16 as they reach and start to leave the location of the pocket 39 and said rolls carry said caps along the forming-flange or rim 11, starting 105 from the point 40, to the diminishing point 41 thereof and after reaching the latter point allow the caps to drop into a chute 42, whence they descend to a suitable place of deposit. The chute 42 has an open upper end, as shown in Figs. 1 and 4. During the travel of the rolls 16 along the recessed flange or rim 11, the springs 23 act with sufficient force against the rolls to cause them to press the caps, at their skirt portions, into the groove 14 of said flange or rim 11 and against the inner surfaces of said rim or flange, the tops of the then inverted caps riding along upon the flat top of the table 10 and successive portions of the skirts of 110 115 120 125 130

the cap being pinched between said rolls and said flange. The rolls 16 are driven along the forming-flange or rim 11 by power, and hence are compelled to make a continuous circuit of the table or plate 10 and during their travel, while pressed outwardly, said rolls effect the rotation of the caps against the forming rim or flange 11, with the result that the skirt portions of the 10 caps are transformed from the straight outline shown in Fig. 2 to the outline shown in Fig. 3. The springs 23 exert outward pressure against the rolls 16 and caps 33 while said rolls and caps are traveling against the 15 inner surfaces of the rim or flange 11, said springs then being compressed by the engagement of the caps and rolls with said rim or flange.

There is a constant rotation of the arms 20 21 carrying the rolls 16, and hence the caps to be transformed in shape are fed one after another to the pocket 39 and are taken up, one after another, from the pocket 39 by the successive rolls as the rolls reach said pocket 25 and moved along the flange or rim 11. The action of the rolls 16 against the caps is both a rolling and spinning operation and the caps finally leave the machine properly recessed, as shown in Fig. 3, and with all their 30 surfaces entirely smooth. In Fig. 1 I illustrate the machine as employing three rolls 16 and three arms 21, but obviously the invention is not limited to any special number of the arms 21 and one arm or half a dozen 35 arms may be made use of, as may be desired, the only essential consideration being that each roll 16 shall have a sufficient length of travel along the forming-flange or rim 11 to properly transform the skirt of the cap carried by the roll from the shape shown in Fig. 2 to that illustrated in Fig. 3 and leave the cap with smooth surfaces.

In Figs. 5 and 6, I illustrate a modification of the invention in which a straight instead of a circular forming-flange or rim 45 43 is made use of in connection with the roll 44 which conforms to the roll 16 hereinbefore described. The forming-flange or rim 43 has the same grooved formation as the rim or flange 11 and extends horizontally from a flat vertical plate or bed 45, and hence the rim or flange 43 does not require specific description. The rim or flange 43 and plate 45 are supported by a right angular frame 46 having a base flange 47 upon which is a spring-cushion 48 which directly receives the forming-flange or rim 43 and acts to press said rim or flange 43 against the roll 44 and cap carried thereby, said roll 50 44 being so positioned that when the cap is thereon, as shown in Fig. 6, and the roll is moved upon the flange 43, it crowds said flange downwardly against the resistance of the spring-cushion 48. In the construction 55 shown in Figs. 5 and 6, the spring-cushion

48 does the same work as the springs 23 in the construction shown in Figs. 1 and 4. The construction shown in Figs. 5 and 6 will be understood from what has been said with respect to Figs. 1 to 4 inclusive without further detailed explanation. 70

In Figs. 7 and 8, I illustrate a further modification of the invention and therein 50 55 denotes a rotary disk having a forming-flange or rim 51 of the identical formation of the rim or flange 11 hereinbefore referred to. The disk 50 is mounted on a shaft 51 which may be driven by a band wheel 52 or other source of power. The roll 53 corresponds with the roll 16 of Fig. 1 and has identical surfaces to match the corresponding surfaces of the forming-rim or flange 51. In Fig. 8 I illustrate the completed cap on the roll 53, said cap having been completed by the travel of the forming flange or rim 51 along said roll, while the roll was held in fixed position but free to rotate. The roll 53 is mounted on the end of a rod 54 carried by a head 55 which is adjustable transversely of the bed-plate 56 by means of a screw 57, whereby the roller 53 may be moved toward or from the rim or flange 51 of the disk 50. A coiled spring 58 is provided on the screw 57 and said screw carries a collar 59 engaging one end of said spring. When the screw 57 is worked rearwardly to carry the collar 59 against the spring 58, the spring becomes compressed and exerts its force to press the roll 53 against the rim or flange 51 of the disk 50. By means of the screw 57, the pressure of the spring 58 may be adjusted so that it will be ample to so force the roll 53 against the skirt of the cap as to press said skirt against the inner forming surfaces of 60 said rim or flange. The screw 57 is carried by a cross-head 60 and this cross-head is adjustable laterally toward and from the disk 50 by means of a screw 61, whereby the roller 53 may be entirely withdrawn from the disk 50 whenever so desired. I present 100 Figs. 7 and 8 to indicate a reversal of the operation of a portion of the mechanism shown in Fig. 1. In Fig. 1 the rim or flange 51 is stationary and the rolls 16 are caused to travel along its forming rim or flange 11, and in Figs. 7 and 8 the rim or flange 51 is the rotary member, while the roll 53 is capable of independent rotation but otherwise 105 stationary. I very greatly prefer the construction shown in Figs. 1 and 4, having used the same with great success. 115

In the several forms of my invention hereinbefore described, it is to be observed that in transforming the plain skirt of the cap 33 shown in Fig. 2, to the shape represented in Fig. 3, the disk top of the cap is not at all distorted, nor is that portion of the skirt numbered 35 in Fig. 3 distorted, but is left in its original shape, said portion 35 being held in its original shape between the shoul- 120 125 130

der 26 of the forming roll and the adjacent surface 13 of the groove 12 in the forming rim or flange 11, as shown at the right hand edge of Fig. 3. The portions of the skirt of the cap which are reshaped by the machines of my invention are the inclined intermediate section 36 and the flange 37 extending from the inner edge thereof. The part 36 is formed inwardly, as shown in Fig. 3, between the inclined surface 28 of the forming roll and the adjacent surface 14 of the rim or flange 11, and the flange 37 is positioned inwardly by the wall 15 of the forming-rim or flange 11 and the wall 29 on the forming-roll, said portions 36, 37 being displaced inwardly along annular lines and creating the recess 34 to receive a gasket to engage the sides of the tumbler or the like to which the cap may be applied. The inclined section 36 of the skirt of the cap provides a shoulder to support the gasket as well as creating the recess 34, which is closed at its lower end by said shoulder. In all the forms of my invention described, the forming rolls are exactly alike and all of them are less in diameter than the plain cap 33 shown in Fig. 2, and in each instance the pressure exerted against the skirt of the cap between the forming-roll and forming-flange is cushioned, this being by the spring 23 of Fig. 4, the cushion 48 of Fig. 6 and the spring 58 of Fig. 8.

What I claim as my invention and desire to secure by Letters-Patent, is:

35. 1. In a machine of the character described for transforming the flat skirt of a partly formed closure-cap into a skirt having an annular recess at its upper end to receive a side-seal gasket, a flat base plate extending outwardly therefrom and having at its inner edge an undercut groove, a forming roll to receive and being less in diameter than the cap and having a shoulder and side surfaces conforming to the groove and surfaces of said forming-flange and adapted to co-operate therewith in forming the annular recess in the skirt of the cap carried on said roll, a coiled spring back of said roll for firmly and yieldingly pressing the roll against the skirt of the cap held tightly between them, whereby the roll and cap are rotated against said flange and the skirt of the cap is given a shape conforming to the forming-surfaces of said flange and roll, and having means back of said roll for cushioning the pressure of the roll against the skirt of the cap.

60. 2. In a machine of the character described for transforming the flat skirt of a partly formed closure-cap into a skirt having an annular recess at its upper end to receive a side-seal gasket, a flat base plate extending outwardly therefrom and having at its inner edge an undercut groove, a forming roll to receive and being less in diameter than the

cap and having a shoulder and side surfaces conforming to the groove and surfaces of said forming-flange and adapted to co-operate therewith in forming the annular recess in the skirt of the cap carried on said roll, 70 means for effecting relative travelling movement between said roll and forming flange with the skirt of the cap held tightly between them, whereby the roll and cap are rotated against said flange and the skirt of the cap 75 is given a shape conforming to the forming-surfaces of said flange and roll, and having a coiled spring back of said roll for firmly and yieldingly pressing the roll against the skirt of the cap and said skirt against the 80 surfaces of said forming flange during the shaping of said skirt.

3. In a machine of the character described for transforming the flat skirt of a partly formed closure-cap into a skirt having an 85 annular recess at its upper end to receive a side-seal gasket, a stationary flat base plate adapted to receive the cap in inverted position and having an edge forming-flange extending at an angle thereto and containing 90 an undercut groove adjacent to said plate, said groove being defined at one end by said plate, at its outer side by a plain wall standing at an angle to the plate and at its other end by an inwardly inclined wall, whence 95 said forming-flange has a plain wall extending outwardly from said inclined wall, a forming roll to receive and being less in diameter than the cap and having a shoulder and side surfaces conforming to said groove 100 and surfaces of said forming-flange and adapted to cooperate therewith in forming the annular recess in the skirt of the cap carried on said roll, a coiled spring back of said roll for firmly and yieldingly pressing the 105 roll against the skirt of the cap and said skirt against the surfaces of said forming flange during the shaping of said skirt, and means for effecting a traveling movement of said roll against said forming-flange with 110 the skirt of the cap held tightly between them, whereby the roll and cap are rotated against said flange and the skirt of the cap is given a shape conforming to the forming-surfaces of said flange and roll, the top of 115 the inverted cap being, during the forming operation, against the upper surface of said flat base plate.

4. In a machine of the character described for transforming the flat skirt of a partly 120 formed closure-cap into a skirt having an annular recess to receive a side-seal gasket, a plate having a forming flange defining an arc of a circle and extending at an angle 125 from the face of the plate and containing an undercut groove of the shape of the desired recess and into which an annular portion of said skirt is pressed, a forming roll to receive and being less in diameter than the cap and having an annular shoulder and side 130

- surfaces conforming to the groove and surfaces of said flange and adapted to cooperate therewith in forming the annular recess in the skirt of the cap carried on said roll, and
- 5 means for effecting the travel of said roll along said forming flange with the skirt of the cap held tightly between them, whereby the roll and cap are rotated against said flange and the skirt of the cap is given a
- 10 shape conforming to the forming surfaces of said flange and roll, the top of the cap during the forming operation being against said plate, the means for effecting the travel of the roll along the flange being a radial
- 15 arm carrying the roll at its outer end and a driven shaft at the center of said circle and to which the inner end of said arm is secured, and said radial arm being in two parts with an interposed spring between them, the outer
- 20 outer part being slid able to permit the spring to press the same and the roll against said forming flange.
5. A machine as claimed in claim 4, in which the means for effecting the travel of the roll along the flange is a radial arm carrying the roll at its outer end and a driven shaft at the center of said circle and to which the inner end of said arm is secured, and in which said radial arm is in two parts with an interposed spring between them, the outer
- 30 part being slid able to permit the spring to press the roll outwardly to a limited extent beyond the starting end of said forming flange and to effect the compression of the spring when the roll is carried against and moved inwardly by the starting end of said flange, whereby the spring is enabled to maintain the roll and cap pressed firmly against the flange during the travel of the roll along said flange.
